Primary Examiner—Robert M. Spear

(74) Attorney, Agent, or Firm—Banner & Witcoff, Ltd.

(57) **CLAIM**

The ornamental design for a pattern for a paper product, as shown and described.

DESCRIPTION

The sole FIGURE is a top plan view of a pattern for a paper product, showing our new design.

The pattern indicated by the attached drawing can be applied to a single or multi-ply product. The uneven broken line showing of the boundary of the claimed region is for illustrative purposes only and forms no part of the claimed design.

1 Claim, 1 Drawing Sheet
